UNITED STATES PATENT OFFICE.

JAMES BENNET, OF ST. JOHNS, CANADA.

IMPROVEMENT IN TEMPORARY BINDERS.

Specification forming part of Letters Patent No. **152,453**, dated June 30, 1874; application filed April 11, 1874.

To all whom it may concern:

Be it known that I, JAMES BENNET, of St. Johns, in the Province of New Brunswick and Dominion of Canada, have invented a new and useful Improvement in Temporary Binders, of which the following is a specification:

The object of this invention is to provide means for preserving, in a safe and convenient manner, papers of all descriptions, as letters, invoices, bills, and all similar papers, as well as newspapers, hand-bills, and cards, and all similar printed matter; and it consists in a file which opens and closes upon the principle of the "parallel ruler," constructed as herein-after more fully described.

In the accompanying drawing, Figure 1 represents a side view of the file. Fig. 2 is a top or plan view.

Similar letters of reference indicate corresponding parts.

This file consists of a bed-piece, A, which rests on the table when the paper is inserted, a clamp, B, of corresponding length, two joint-bars, C C, by which the parts A B are connected, and the pointed holding-pins D D. These pins may be attached to the bed-piece A in any suitable manner, so as to stand firm and rigid, and perpendicular to the bed-piece. In this example of my invention I fasten a metallic strip, E, on top of the bed-piece. Recesses G are made in the bed to admit disks H under the metallic strip, and disks I are placed on top of the strip, screw-threads are cut on the pins, and the disks serve as screw-nuts, into the center of which the pins are screwed, one disk-nut being below and one

above the strip for each pin. The screw-threads are cut the whole length of the pins, and the roughened surface thus produced prevents the papers from too easily slipping up when the clamp is raised. J J are mortises through the clamp B, which receive the pins D D when the clamp is pressed down in filing. When the clamp is raised for filing, the bars C C serve as guides for the edge of the paper, so that the back edges of the papers filed present an even and uniform appearance. By means of the joint-bars the bed A and the clamp B work together the same as the two parts of a parallel ruler.

It is obvious that a quantity of papers thus filed, may be securely bound by taking the lower disk-nuts off and screwing them on to the tops of the pins, and then supplying other pins for the bed-plate; or other pins, wires, or strings, may be inserted through the holes made in the papers, as may be deemed best.

Having thus described my invention, I claim as new and desire to secure by Letters Patent—

1. The combination, with a paper-file bed and clamp, of bars C C, pins D D, strip E, and nuts I H, as and for the purpose specified.

2. The metallic strip E, disk-nuts I and H, and holding-pins D D, in combination with the bed and clamp of a paper-file, as shown and described.

April 1, 1874.

JAMES BENNET.
